UNITED STATES PATENT OFFICE.

JAMES CARVILL GORMAN, JR., OF MANSFIELD, OHIO, ASSIGNOR TO BARNES MANUFACTURING COMPANY, OF MANSFIELD, OHIO, A CORPORATION OF OHIO.

DOUBLE-ACTING SINGLE-CYLINDER PUMP.

1,323,749.

Specification of Letters Patent.

Patented Dec. 2, 1919.

Application filed June 6, 1919. Serial No. 302,264.

To all whom it may concern:

Be it known that I, JAMES CARVILL GORMAN, Jr., a citizen of the United States, residing at Mansfield, in the county of Richland and State of Ohio, have invented certain new and useful Improvements in Double-Acting Single-Cylinder Pumps; and I do hereby declare the following to be a full, clear, and exact description of the invention, such as will enable others skilled in the art to which it appertains to make and use the same.

This invention relates to pumps, and more particularly to double acting single cylinder belt-driven power pumps.

In belt-driven pumps of this type as heretofore ordinarily constructed, it is a common practice to cast the bearings for the driving shaft and the counter-shaft on a rear head which is bolted to the cylinder, so as to sustain the shaft bearings, and to afford access to the rear end of the cylinder, it is necessary to remove not only the head, but also the connecting rods and all of the driving gearing on the rear, which requires considerable time, inasmuch as about one-half of the pump is dismantled. In another design or construction the rear end of the cylinder is cast solid, that is, without a removable head, and in order to afford access to the rear end of the cylinder, it is necessary to take off the connecting rods and also the front cylinder head and to withdraw the piston, which also requires about one-half of the pump to be dismantled.

The primary object of my invention is to obviate these objections and provide a simple, efficient and durable pump of the character referred to, consisting of few parts assembled in compact form, so as to occupy comparatively little space, and having bearings, for both the driving shaft and the countershaft through which motion is imparted to the piston, integral with the cylinder casting or pump body; the cylinder being provided with a rear detachable head so that to afford access to the cylinder, it is only necessary to remove a single fastening bolt without disturbing the connecting rods or driving gear. A further object is to use only a single gear drive instead of the double gears ordinarily employed.

The invention will first be hereinafter more particularly described, with reference to the accompanying drawings, which form a part of this specification, and then pointed out in the claims at the end of the description.

In said drawings:—

Figure 1 represents a top plan view of a pump embodying my invention;

Fig. 2 is a vertical sectional side elevation of the same;

Fig. 3 is a front vertical sectional elevation of the same;

Fig. 4 is a plan view of the pump body or casing having all of the parts shown integral therewith, the working parts being removed;

Fig. 5 is a vertical longitudinal sectional elevation; and

Fig. 6 is a vertical transverse sectional elevation taken at right angles to the view shown in Fig. 5.

Referring to said drawings, in which the same reference letters are used to denote corresponding parts in different views, the letter A may denote the pump body, which is cast integrally with substantially semi-circular upper and lower shaft bearing members or shaft bearings B and B¹ to

which similar detachable members are bolted, as shown in Fig. 2 to complete the bearings for the two shafts C and C¹. The half bearings are each provided with apertured lugs or end portions to receive fastening bolts by which the opposed substantially semi-circular members are bolted to the correspondingly shaped fixed members

and the shafts C and C¹ are journaled in these bearings in close proximity to the pump body, one being arranged slightly above the other, as shown, so as to shorten the pump. The letter D denotes an open

ended cylinder, the rear end of which is closed by a detachable head d, which is firmly secured in place and adapted to be easily removed to permit access to the cylinder by means of a cross-bar or bolster E and a set screw passing through said bolster and bearing on said head. The bolster

is slidably supported on ribs or guideways E¹ preferably cast integrally with or rigidly secured to rearwardly projecting arms car-

rying the shaft bearing B¹; said arms being integral with the pump body or casing and open ended cylinder.

The pump body or casing is formed or provided with a base portion or supporting legs, preferably cast integral therewith and having apertured lugs or flanges on their lower ends to receive fastening bolts by which said body may be firmly secured to the floor of the building or other foundation on which the pump is mounted. The pump body has formed therein an inlet opening *a* which is conveniently located below and midway of the cylinder D, and with an outlet or discharge opening *a'* which is preferably arranged directly opposite the forward discharge valve, in order to permit the use of pulleys on the counter-shaft without interfering with the discharge pipe. The open ends of the pump cylinder are in communication with said inlet and discharge openings through waterways at opposite ends of the cylinder and cast integrally therewith, said waterways being provided with suitable openings to receive the usual check valves through which water is drawn in and discharged at each stroke of the piston in the usual manner; said inlet and discharge openings being connected in any suitable manner with suitable inlet and discharge pipes (not shown). The pump body has also mounted thereon an air chamber F, which may be conveniently secured thereto by means of three bolts fitted in bifurcated lugs, one at the front and one at each side thereof, as shown more clearly in Figs. 1 and 2 of the drawings.

The driven shaft C¹ receives its motion from a counter-shaft C to which power is applied, preferably by means of a belt running over a pulley G, which is fast on the shaft C and beside which is placed a loose pulley G¹ onto which the belt may be shifted when it is desired to stop the pump by any of the means ordinarily employed for that purpose. A pinion *c* on one end of the power shaft C meshes with a gear wheel *c'* on the adjacent end of the driven shaft C¹ which carries a crank pin having a pivotal connection with one end of a pitman rod H, the other end of which is pivotally connected with a reciprocating cross-head I to which the forward end of the piston rod K is secured. The shaft C also carries a crank wheel C² having a pin *c'* for pivotal connection with the connecting rod H¹ which is also pivotally connected at its forward end with one end of the cross-head I, whereby a reciprocatory movement is imparted to the pump piston by the rotation of the driving and driven shafts. The shaft bearing B, which is cast integrally with the pump body or casing, has a lateral extension b¹ in order to support the belt driven pulley at one side of the pump

body clear of the working parts of the pump, 65 and a web or rib b² is cast integral with said extension, whereby it is firmly braced to prevent breakage due to excessive strain thereon.

I thus provide a very simple, efficient, inexpensive, strong and durable double acting single cylinder belt-driven power pump having the bearings of both the driving shaft and the counter-shaft integral with the cylinder, together with a single gear drive 75 instead of the usual double gears, and access to the rear end of the cylinder is afforded by simply removing a single bolt and thereby permit the removal of the detachable head without touching the gearing in any 80 way or removing other parts of the pump and the pump consists of few parts, at least five or six less than are used in pumps of the same general character as heretofore ordinarily constructed, thus simplifying the 85 construction and lessening the cost of manufacture and at the same time reducing the size of the pump so that it will occupy less space than double acting single cylinder belt-driven pumps as heretofore constructed. 90

Having thus described my invention, what I claim as new and desire to secure by Letters Patent of the United States, is:—

1. A pump body or casing for a double-acting single cylinder belt-driven power 95 pump having a cylinder open at both ends and having an inlet opening below said cylinder, a discharge opening at the top of the casing, and waterways in communication with said openings and the open ends 100 of the cylinder all in one integral structure, together with integral shaft bearings consisting of substantially semi-circular bearing members located in the rear of the cylinder, one above the cylinder and the other 105 substantially in alignment therewith and slightly in rear of the upper bearing; the upper bearing having an extension at one side of the casing and a diagonal web or rib connecting said extension with said body 110 and integral therewith.

2. A double-acting single cylinder pump comprising a pump body or casing having the cylinder and shaft bearings integral therewith, said bearings consisting of substantially semi-circular bearing members located in the rear of the cylinder, one above the cylinder and the other substantially in alignment therewith, the upper bearing being extended laterally beyond one side of 120 the casing and formed with a horizontal web or rib connecting it with said body and integral therewith.

3. A double-acting single cylinder pump comprising a pump body or casing having a 125 cylinder and shaft bearings integral therewith, said cylinder being open at both ends and formed integrally with waterways lead-

ing therefrom to an inlet opening below the cylinder and to an outlet opening at the top of the casing, and said bearings consisting of substantially semi-circular bearing members 5 located one above the plane of the cylinder and the other slightly in the rear of the cylinder, the upper bearing having an extension projecting beyond one side of the pump body and a horizontal web or rib con-

necting said extension with said body and 10 integral therewith, so as to firmly brace and prevent breakage of said extension.

In testimony whereof I affix my signature in the presence of two witnesses.

JAMES CARVILL GORMAN, JR.
